Fig. 4

The rear and side elevational views of the bottle not shown are the same as that illustrated in FIGURES 1 and 2, respectively. The dominant features of our design reside in the portions shown by solid lines.

We claim:

The ornamental design for a bottle, substantially as shown and described.
